UNITED STATES PATENT OFFICE.

GEORGE S. GATCHELL, OF ROSELLE PARK, NEW JERSEY, ASSIGNOR TO THE SINGER MANUFACTURING COMPANY, A CORPORATION OF NEW JERSEY.

WORK-GUIDING MECHANISM FOR SEWING MACHINES.

Application filed October 22, 1917. Serial No. 197,763.

To all whom it may concern:

Be it known that I, GEORGE S. GATCHELL, a citizen of the United States, residing at Roselle Park, in the county of Union and 5 State of New Jersey, have invented certain new and useful Improvements in Work-Guiding Mechanisms for Sewing Machines, of which the following is a specification, reference being had therein to the accompanying drawings.

This invention relates to sewing machines, more particularly of the multiple-needle cylinder-bed type adapted for joining and covering abutted knit goods edges in one 15 operation, as disclosed in my copending application Serial No. 185,446, filed April 10, 1917.

In the use of such machines for the manufacture of underwear from knitted fabric 20 it is found that seams formed lengthwise of the wales are strongly resistant to deformation when subjected to lateral stress, there being no observable tendency for the seam to open up or "grin" along the center 25 line where the cut edges are usually abutted. The secure holding properties of such a seam formed lengthwise of the wales is usually considered to be due to the fact that the body-fabric material yields readily to 30 stresses crosswise of the wales and, under these conditions, is more elastic than the seam. When, however, the seam is formed cross-wise of the wales it has a tendency to "grin" when subjected to excessive lateral 35 stress. This tendency is probably due to the fact that the seam is more elastic laterally than the fabric; the stress in the latter case being transmitted to the seam in a direction lengthwise of the wales of the body- 40 fabric.

The present improvement has for a particular object to provide a machine of this class with work-guiding mechanism which, when it is desired to stitch crosswise of the 45 wales of the body-fabric, may be readily thrown into action or effective position to facilitate the presentation of the knit-goods edges in overlapping relation to the needles, whereby the resulting seam may yield to a 50 transverse stress without opening-up.

Among the more general objects of the invention may be mentioned the provision of an edge-guide which may be readily thrown or shifted from effective to ineffect- 55ive position and vice versa, and which is

particularly adapted for guiding the under of two overlapping plies of material to the stitch-forming mechanism.

A further object is to combine an edge-guide with a trimming mechanism so as to 60 guide an edge of one ply of material into underlapping relation with an upper ply of material acted upon by said trimming mechanism.

The invention, in its preferred embodiment, is incorporated in a machine having substantially the constructive features disclosed in my said copending application and comprising stitch-forming mechanism of the four-needle seam-covering type and 70 trimming mechanism adapted to trim off the upturned marginal portions of material as said portions pass along the space between the toes of the presser-foot. The present edge-guide is formed with an edge-guiding 75 surface and preferably with an overhanging work-confining lip and is preferably so mounted relatively to the line of seam-formation that the edge-portion of an underlapping ply of material may be guided with- 80 in the range of action of all of the needles except one. In other words, the edge-guide is so placed that the edge of the underlapping ply will extend well across the center 85 line of the seam and terminate short of the outer row of needle-thread loops. Means are provided whereby the guide may be readily thrown into action when it is desired to lap the goods, and out of action when it is desired to abut the goods. 90

In the accompanying drawings, Fig. 1 is a perspective view of the invention as embodied in a machine such as disclosed in my said copending application. Fig. 2 is a plan view of the throat-plate of the machine 95 showing the work-guiding mechanism mounted thereon. Fig. 3 is a side elevation of the same. Fig. 4 is a bottom plan view. Fig. 5 is an end elevation of the guiding mechanism and Fig. 6 is a cross sectional 100 view of a seam such as shown in Fig. 1.

In the present instance the invention is embodied in a machine having a cylinder-bed or work-supporting arm 1 at whose free end is supported a throat-plate 2 and an 105 end-cap 3. The throat-plate is formed in advance of the apertures for the needles n' , n^2 , n^3 , n^4 with a centrally disposed ridge 5 the sloping sides of which cooperate with the beveled inner surfaces 6 of the spaced 110

presser-foot toes 7 of the sole piece 8 pivoted at 9 to the shank 9' to guide the up-turned marginal portions of material to the trimming mechanism 10 so that bunching of the material along the center line of seam may be largely avoided and the cut-edges pressed down, joined and covered in closely abutted but not over-crowded relation. The machine also includes the single looper *o* the covering thread-fingers 11 and the trimming chute 12 carried by the usual head 13, all as more fully explained in my said co-pending application.

The edge-guiding mechanism comprises an edge-guiding element having preferably a vertically disposed flattened shank 14 mounted within a suitable slideway 15 in a guide-block 16 secured to the under side of the throat-plate by a screw 17. The shank 14 of the edge-guiding element is formed with an elongated slot through which passes the headed screw 18 threaded into the block 16 and serving to retain the shank 14 in said slideway.

The throat-plate is in the present instance formed in alignment with the slideway 15 with an aperture through which projects the upper operative end-portion of the edge-guiding element; the latter being formed with an edge-guiding surface 19 and preferably with an overhanging work-confining lip 20. The surface 19 preferably is so located relatively to the line of seam that the edge of the material guided thereby will pass between the needles *n'* and *n²* but as near as feasible to the outer needle *n'*. In Fig. 5 the guiding surface 19 is shown slightly to the left of the path of the needle *n'*, the reason being that the ridge 5 will act to draw the edge of the overlapping ply to the desired position to the right of the needle *n'*, as will be readily understood.

In the present instance, the guide-element is urged toward elevated or operative position by means of a curved leaf-spring 21, one end of which is secured to the block 16 and the other end of which bears upwardly against the lateral pin 23 secured to the shank 14 of the guide-element. The pin 22 is adapted to strike the lower side of the guide-block 16 and limit the upward movement of the guide-element, as shown in Fig. 5, thus determining the effective position of the edge-guide.

The side of the block 16 in contact with the throat-plate 2 is cut away at 23 to receive the spring-pressed latch-lever 24 formed with a pointed latching nose 25 which is adapted to snap over the shoulder 26, afforded by the beveled or notched portion 27 of the shank 14 of the guide-element, to detain the latter in depressed or inoperative position. The forward end of the latch-lever 24 preferably extends to the exterior of the work-arm through a notch 28

in the end-cap 3 and may be readily manipulated as a finger-piece to release the guidelement and permit it to spring upwardly to operative position. When the use of the guide-element is not desired it may be readily depressed to inoperative position, as shown in dotted lines in Fig. 3, in which position it will be retained by the latch-lever 24.

The guiding mechanism may thus be used to secure the formation of the seam illustrated in Fig. 6 in which two fabric sections *a*, *b* have their meeting edges overlapped and united by a four-needle single looper mechanism. The edge *a'* of the fabric section *a* lies substantially at the center line of the seam while the edge *b'* of the fabric section *b* extends well across the center line of the seam and under the fabric section *a*. The row *s'* of needle-loops of the needle *n'* extends only through the fabric section *a* but close to the edge *b'* of the fabric section *b*. The row *s²* of needle-loops extends through both plies *a* and *b* and the rows *s³* and *s⁴* of needle-loops extend only through the fabric section *b*. The usual covering thread or threads *c* are incorporated in the seam at the upper side of the material while the usual looper-thread *t* is concatenated with the needle-loops at the under side of the material.

It will be seen that the entire mechanism of the work-guide, with the exception of the upper end of the guide-element and the tip end of the latch-lever 24, is housed within the work-arm. Consequently there are no projecting parts liable to catch the work or interfere with its passage along the work-arm. The present guide may be instantly and with certainty thrown into or out of action and the mechanism thereof is not liable to become clogged with lint and rendered ineffective. It is to be understood that the present guiding mechanism, while particularly adapted for use in cylinder-bed machines, is of general utility and may be used to advantage upon sewing machines of various types.

Having thus set forth the nature of the invention, what I claim herein is:—

1. In a sewing machine, in combination, stitch-forming mechanism, presser-mechanism including spaced toe-portions between which upturned marginal portions of material are adapted to pass, trimming mechanism adapted to trim said marginal upturned portions of material, and an edge-guide having an edge-guiding wall disposed at one side of the center line of seam-formation in advance of said presser-foot and adapted to guide an edge-portion of material into underlapping relation with an upper ply of material acted upon by said trimmer.

2. In a sewing machine, in combination,

- stitch-forming mechanism including a plurality of reciprocating needles and complementary loop-taking means, presser-mechanism including spaced toe-portions between which upturned marginal portions of material are adapted to pass, trimming mechanism adapted to trim said upturned marginal portions of material, and an edge-guide having an edge-guiding wall disposed at one side of the center line of seam-formation in advance of said presser-foot and adapted to guide an edge portion of material into underlapping relation with an upper ply of material acted upon by said trimmer, said edge-guide also having an overhanging work-confining lip and being depressible to inoperative position.
3. In a sewing machine, in combination, stitch-forming mechanism including a plurality of reciprocating needles and complementary loop-taking means, presser-mechanism including spaced toe-portions between which upturned marginal portions of material are adapted to pass, trimming mechanism adapted to trim said marginal upturned portions of material, and an edge-guide having an edge-guiding wall disposed at one side of the center line of seam-formation in advance of said presser-foot and adapted to guide an edge-portion of material into underlapping relation with an upper ply of material acted upon by said trimmer, said edge-guide also having an overhanging work-confining lip and being depressible to inoperative position, and means for retaining said edge-guide in depressed or inoperative position.
4. A sewing machine having in combination a frame including a work-supporting arm, stitch-forming mechanism including a reciprocating needle operating at the free end of said work-supporting arm, an edge-guide mounted on said arm in advance of said needle, means for moving said edge-guide to operative position, and manually controlled means for detaining said edge-guide in inoperative position.
5. A sewing machine having in combination a frame including a tubular work-supporting arm, stitch-forming mechanism including a reciprocating needle operating at the free end of said work-supporting arm, an edge-guide mounted on said arm in advance of said needle, means for moving said edge-guide to elevated position, and manually controlled means for detaining said edge-guide in depressed position, said means being disposed mainly within said work-arm and including a finger-piece having an accessible portion at the exterior of said work-arm.
6. A sewing machine having in combination a frame including a tubular work-supporting arm, stitch-forming mechanism in- cluding a reciprocating needle operating at the free end of said work-supporting arm, an upwardly spring-pressed edge-guide mounted on said arm in advance of said needle, and a latch for detaining said edge-guide in depressed position said latch being disposed mainly within said work-arm and including a finger-piece accessible at the exterior of said work-arm.
7. A sewing machine comprising, in combination, a frame formed with a work-arm including an elongated throat-plate disposed at the free end of said work-arm, stitch-forming mechanism including a reciprocating needle operating through an aperture in said throat-plate, and an edge-guide sustained by said throat-plate for movement from inoperative or depressed position to operative or elevated position and vice versa.
8. A sewing machine comprising, in combination, a frame formed with a work-arm including an elongated throat-plate disposed at the free end of said work-arm, stitch-forming mechanism including a reciprocating needle operating through an aperture in said throat-plate, a vertically movable edge-guide sustained by said throat-plate in front of the needle, means for moving said edge-guide to operative position, and manually controlled means for detaining said edge-guide in inoperative position.
9. Work-guiding mechanism for sewing machines comprising a work support, a rigidly held guide-element vertically movable in said support from operative to inoperative position and vice versa, a spring urging said guide-element toward one of said positions, and a latch for detaining said guide-element in the other of said positions.
10. Work-guiding mechanism for sewing machines comprising a support, a guiding element sustained by said support in advance of the stitching point and movable within the same, a spring urging said guiding element toward operative position, and a manually controlled latch-lever mounted on said support and adapted to detain said guiding element in inoperative position.
11. Work-guiding mechanism for sewing machines comprising an apertured throat-plate, a block mounted at the under side of said throat-plate, a work-guide slidably mounted on said block and having an operative work-guiding portion projecting through said aperture and extending in the direction of feed, and depressible means for elevating said work-guide to operative position.
12. In a sewing machine, in combination, stitch-forming mechanism, trimming mechanism, means for feeding upturned edge portions of material to said trimming mechanism, and means movable at will into the path of one of said portions for guiding the

same into underlapping relation with the other and out of cooperative relation with the trimming mechanism.

13. In a sewing machine, stitch-forming mechanism, trimming mechanism, means for directing edge-portions of material toward said trimming mechanism, and means disposed at one side of the center line of seam-formation and movable at will from ineffective to effective position to guide one of said edge-portions of material into underlapping relation to the other and away from the finished mechanism to prevent trimming thereof.

14. In a sewing machine, stitch-forming mechanism, trimming mechanism, means for feeding upturned edge portions of material to said trimming mechanism, and means disposed at one side of the center line of seam-formation for guiding one of said edge portions into underlapping relation to the other and out of cooperative relation with the trimming mechanism, said guiding means being movable into and out of operative position.

15. Work-guiding mechanism for sewing machines comprising a work support, a movable guide carried by said support, a spring for moving said guide into operative position, a shoulder on said guide, and a spring-pressed latch mounted within and operable exteriorly of said support adapted to engage said shoulder to hold said guide in inoperative position.

16. In a sewing machine, in combination, stitch-forming mechanism, trimming mechanism, means for guiding two marginal portions of material to the trimming mechanism and then to the stitch-forming mechanism in abutting relation, and means movable from an ineffective to an effective position and

adapted when in the effective position to prevent the guiding of one portion of material to the trimming mechanism, and to cause the guiding of the two portions to the stitch-forming mechanism in overlapping relation.

17. In a sewing machine, in combination, stitch-forming mechanism, trimming mechanism, means adapted to guide two marginal portions of material to the trimming mechanism and then to the stitch-forming mechanism in abutting relation, and means movable at will from ineffective to effective position to guide one portion away from the trimming mechanism to prevent trimming thereof and to direct said portion into lapped relation with the other portion.

18. In a sewing machine, in combination, stitch-forming mechanism, trimming mechanism, means for guiding two marginal portions of material to the trimming mechanism and then to the stitch-forming mechanism in abutting relation, and means in advance of the trimming mechanism movable from an ineffective to effective position at will for guiding one portion away from the trimming mechanism.

19. In a sewing machine, in combination, stitch-forming mechanism comprising a plurality of needles, substantially horizontally acting trimming mechanism located in advance of the needles, means adapted to guide two upturned marginal portions of material to the trimming mechanism and a guide movable from ineffective to effective position to direct one marginal portion of material beneath the trimming mechanism and into underlapping relation to the trimmed portion.

In testimony whereof, I have signed my name to this specification.

GEORGE S. GATCHELL.
